(57) **CLAIM**

The ornamental design for an operating sheath, as shown and described.

DESCRIPTION

FIG. 1 is a front perspective view of an operating sheath according to the present invention.

FIG. 2 is a left side view of the operating sheath of FIG. 1. FIG. 3 is a right side view of the operating sheath of FIG. 1. FIG. 4 is a top view of the operating sheath of FIG. 1. FIG. 5 is a bottom view of the operating sheath of FIG. 1. FIG. 6 is a front view of the operating sheath of FIG. 1; and, FIG. 7 is a rear view of the operating sheath of FIG. 1.

The dashed lines illustrate environment that does not form a part of the present invention, and no claim is made to the material illustrated with dashed lines.
